(57) **CLAIM**

The ornamental design for a timer, as shown and described.

DESCRIPTION

FIG. 1 is a bottom view of a timer showing my new design;

FIG. 2 is a front view thereof;

FIG. 3 is a top view thereof;

FIG. 4 is a left view thereof;

FIG. 5 is a right view thereof;

FIG. 6 is a rear view thereof; and,

FIG. 7 is a perspective view of the timer.

The broken lines portion of the figure drawings is included to show unclaimed subject matter only and forms no part of the claimed design.
